(57) CLAIM

The ornamental design for a key hook, as shown and described.

DESCRIPTION

FIG. 1 is a perspective view of a key hook showing our new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof; and,

FIG. 7 is a bottom plan view thereof.

The broken lines are included for the purpose of illustrating unclaimed portions of the structure and form no part of the claimed design.

1 Claim, 2 Drawing Sheets
